UNITED STATES PATENT OFFICE.

HOWARD D. COLMAN, OF ROCKFORD, ILLINOIS, ASSIGNOR, BY MESNE ASSIGNMENTS,
TO EDGAR S. NETHERCUT, OF EVANSTON, ILLINOIS.

WARPING.

Application filed September 10, 1917, Serial No. 190,501. Renewed February 10, 1923.

To all whom it may concern:

Be it known that I, HOWARD D. COLMAN, a citizen of the United States, residing at Rockford, in the county of Winnebago and 5 State of Illinois, have invented certain new and useful Improvements in Warping, of which the following is a specification.

This invention relates to the winding of 10 yarn upon a warp beam from individual yarn masses which rotate to supply the yarn.

By means of inventions disclosed in prior 15 patents granted to me, the time required to replenish a warper creel has been much reduced and the winding speed has been increased to several times that heretofore possible, whereby production has been greatly increased. The present invention has for 20 its general object to increase production still further by reducing the time consumed in connecting new supply yarn masses to an empty warp beam, and in separating the completed beam from the supply yarn masses. In attaining this object the detectors that cause stoppage of the apparatus 25 in case of breakage or undue slackness of the threads have been so located and so constructed that the threads may be operatively associated with their respective detectors in the simple act of drawing the 30 threads from the newly replenished creel to the beam. In the present embodiment of the invention, the detectors are mounted upon the creel in close proximity to their respective supply yarn masses. 35 The detectors have been arranged to close an electric circuit upon the breakage or undue slackening of the threads, thereby obviating the use of much mechanism which otherwise would be necessary owing to the 40 wide distribution of the detectors and effecting more prompt actuation of the creel brakes, the beam brake and the mechanism that throws out the drive for the warper.

One of the objects of the invention is to 45 provide means for exerting a light pressure upon the supply yarn masses to prevent coasting thereof while the warper is being operated at low speed or in case the threads be casually disturbed.

50 Further objects and advantages of the invention will be apparent from the following disclosure of one embodiment thereof.

In the accompanying drawings, Figure 1 55 is a side elevation of an apparatus embody-

ing the features of my invention, many of the supply yarn masses and associated parts being omitted for the sake of clearness. Fig. 1^a is a fragmental view of a comb that may be used on the warper. Fig. 2 is a top plan view of the apparatus, the resetting mechanism and the devices for supporting extra cheeses being omitted. Fig. 2^a is a view of the beam brake. Fig. 2^b illustrates one way in which the threads may be guided in passing from the creel to the warper. Fig. 3 is a top plan view of the creel. Fig. 4 is a fragmental perspective view illustrating the pivot for the lower end of each gate and the stops for limiting swinging movement of the gate. Fig. 5 is a fragmental transverse vertical sectional view of the creel. Fig. 6 is a horizontal sectional view taken in the plane of dotted line 6 of Fig. 7. Fig. 7 is a view generally similar to that of Fig. 5. Fig. 8 illustrates two of the detectors with which the creel is provided. Fig. 9 is an inner side view of a portion of the creel showing the braking mechanism. Fig. 10 is a fragmental sectional view of one of the creel brakes. Fig. 11 is a sectional view taken in the plane of dotted line 11 of Fig. 10. Fig. 12 is a section on dotted line 12 of Fig. 10. In Figs. 11 and 12 the brake may be assumed to be moving into 50 braking position, having touched the cheese. Fig. 13 is a view similar to Fig. 12, but showing the braking pressure as being applied. Figs. 14 and 15 illustrate one of the detectors and the circuit-closer operated thereby. Fig. 16 illustrates a part of the electrical connections between the detectors and the electromagnet. Fig. 17 is a fragmental top plan view of one of the gates with which the creel is provided. Fig. 18 is a section on dotted line 18 of Fig. 15. Fig. 19 is a fragmental top plan view of a detector showing how the detector may draw the thread into loops to take up slack in the thread. Fig. 20 is a fragmental view of some of the operating connections between the resetting mechanism and the warper. Fig. 21 is a side elevation of the resetting mechanism. Fig. 22 is an elevation of the opposite side of said mechanism. Fig. 23 is an end elevation of the resetting mechanism looking from the left-hand side of Fig. 22. Fig. 24 is a fragmental view of the resetting mechanism showing the parts in the drag pressure position. Fig. 25 is a top 100 105 110

plan view of a belt shifter comprised in the resetting mechanism. Fig. 26 is a top plan view of the devices for applying the brakes. Fig. 27 is a fragmental view of the resetting mechanism showing approximately the position assumed by certain parts when the brakes are applied. Fig. 28 illustrates a brake for the resetting mechanism. Fig. 29 is a section on line 29 of Fig. 26. Fig. 30 is a section on line 30 of Fig. 26. Fig. 31 is a view on dotted line 31 of Fig. 26. Fig. 32 is a fragmental top plan view of the driving mechanism for the warper. Fig. 33 is a vertical sectional view taken approximately in the plane of dotted line 33 of Fig. 32. Fig. 34 contains a diagram of the electrical circuits used in this apparatus and illustrates in vertical section a speed-controlled switch included in the circuits. Fig. 35 is a top plan view of certain parts shown in Fig. 33.

While the invention is applicable to the rewinding of various forms of yarn masses, it is herein disclosed as embodied in a machine for rewinding yarn masses in the form of cylindrical cheeses *a* (Fig. 6). Each cheese consists of yarn spirally wound upon a tubular core *b*. The creel in which the cheeses are mounted may be of any suitable construction, that herein shown being generally similar to the creel disclosed in Patent No. 1,207,138, dated December 5, 1916. The cheeses are rotatably supported upon spindles 1 (Fig. 5), four cheeses in the present embodiment being carried by each spindle. The cheese cores are not mounted directly upon the spindles, but are carried by rollers 2 which are rotatably supported upon the spindles. Preferably ball bearings are interposed between the rollers 2 and the spindles, in order that the cheeses may revolve with great freedom. It will be understood, however, that in certain aspects the present invention is independent of the particular means herein shown for supporting the supply yarn masses.

In the construction herein illustrated, the spindles 1 are arranged in groups of three, each group being fixed to a base 4 (Figs. 5 and 6). Each base 4 with its rows of spindles 1 will hereinafter be termed a trident. The tridents are removable from the framework of the creel and are adapted to be used at the winder as a receptacle for the cheeses when the latter are removed from the winder.

The framework of the creel may be of any suitable character, although the construction herein disclosed is very advantageous. As herein shown, it consists of two upright frames 6 and 7 (Fig. 2) which are adjacent each other at one end and separated from each other at the opposite end so as to constitute a V-shape structure. The frames 6 and 7 are suitably braced and con-

nected together. In the particular embodiment selected for illustration, each of the frames 6 and 7 is composed of six bays, each adapted to support three tridents arranged one above the other. The tridents are insertable and removable through the outer sides of the frames 6 and 7. At the left-hand side of each bay are sockets 8 (Figs. 5 and 6) each intended to receive one end of the base 4 of a trident. At the right-hand side of the bay are sockets 10 (Fig. 5) to receive the tips of the spindles. As will be apparent from Figs. 1 and 2, the spindles 1 are disposed horizontally and extend longitudinally of the frames 6 and 7. Each bay is provided on its outer side with a hinged gate 12 (Fig. 3). The gate may be pivoted in any suitable manner. The present embodiment comprises a pivot for the lower end of the gate, as shown in Fig. 4, 13 being a pivot pin secured to a frame bar 14. The gate is held out of contact with the frame bar 14 by means of an annular flange or washer 15 on the pin 13. The extent of the opening movement of the gate is limited by a stop 16 secured to the frame bar 14. The closed position of the gate is determined by a stop 17 secured to the frame bar 14. The upper end of the gate consists of a cross-bar 18 (Fig. 16) which has an opening through which a pivot pin 19 extends. Said pivot pin is carried by a casting 20 (Fig. 7) which is rigidly secured in the creel framework. The gate is held shut by means of a latch 21 pivoted to the casting 20 at 22, said latch being arranged to engage the end of the bar 18 as shown in Figs. 6 and 7. 23 is a tension spring which normally holds the latch in engagement with the gate. 24 is a stop to limit the action of the spring. The latch is provided with a handle 25 for use in releasing the gate. The latch 21 holds the gate pressed against the stop 17, thus preventing vibration of the gate.

The means for detecting exhaustion or excessive slackness of the yarn extending from the cheeses *a* to the section beam *B* comprises detectors mounted upon the gates 12, there being a detector for each cheese. The detectors for each vertical row of cheeses are mounted upon a support which may have the form of an upright square tube 26 (Figs. 15 and 18). Each gate comprises four such tubes. Each detector consists of an arm 27 (Fig. 15) preferably formed of a piece of wire bent to provide a pivot 28, the arm being in the form of a loop so as to provide two parallel portions against which the thread bears. These parallel portions are bent so as to provide notches 29 (Fig. 14) through which the thread may run. As best shown in Fig. 6, the detector or pivoted arm 27 is located in the vertical plane in which the cheese rotates. The thread changes direction at the the detector and runs to a

comb on the warper. The tension of the thread normally holds the arm 27 in contact with a stop rod 30 against the action of gravity. At the side toward which the arm 27 tends to fall are two plates 31 and 32, against the edges 33 of which the thread is carried by the arm 27 if the thread becomes slack. As the arm 27 swings down, the thread is drawn into the form of two loops, 10 as shown in Fig. 19. 34 is a guide plate which, like the plates 31 and 32, is secured to the tube 26, the upper portions of said plates being parallel. The plates 32 and 34 are secured together by the stop rod 30. The 15 arm 27 extends above the plates 31, 32 and 34. In the warper-replenishing operation, the thread passes into operative relation to the detector by moving upwardly along the curved edge 35 of the plate 34, the edge 35 20 serving to guide the thread into the notch 29 of the adjacent portion of the arm 27. The rounded upper end of the plate 32 allows the thread to spring over the upper end of said plate 32 into contact with the 25 sloping upper end of the arm 27, the thread being thus guided into the space between the arm 27 and the edge 33.

When the arm 27 falls into the dotted-line 30 position indicated at *x* in Fig. 14, an electric circuit is closed, whereby the brakes are released to action. A contact arm 36 is attached to the pivot 28 of the arm 27 and is arranged to swing into contact with an electric conductor 37 extending longitudinally of and within the tube 26.

When the creel is not entirely filled, it is necessary to render the unused detectors inoperative. For this purpose the contact arm 36 is preferably made in the form of 40 a spring clip embracing a flattened portion of the pivot 28. To place an unused detector out of action, the operative swings the arm 27 from the dotted-line position indicated at *x* in Fig. 14 to a position about 45 180 degrees distant from the full-line position shown in said figure, in the course of which movement the pivot 28 rotates within the clip 36 until the said pivot has made a little more than a quarter of a revolution 50 within the clip, when the resiliency of the clip causes the clip to swing through the remainder of the half revolution. The arm 27 may then be permitted to swing freely into the position shown at *y* in Fig. 14, in 55 which position the arm 36 is out of contact with the conductor 37. To restore the detector to operative condition, the arm is swung up into contact with the stop 30, in 60 which movement the arm 36 is carried against one wall of the tube 26, the continuing upward movement of the detector arm 27 causing relative rotation between the pivot 28 and the arm 36 until the latter snaps into normal relation to said pivot.

65 It will be apparent that the tube 26 serves

to enclose the contacts 36 and conductors 37 and thus keeps said parts free from dust and lint. It will also be seen that each tube 26 and its contained conductor 37 and contacts 36 constitute a series of enclosed electric switches. 70

In warpers of the prior art where electric stop motions were employed, it was necessary to use a current of relatively low voltage for the reason that the electric contacts 75 were exposed and the use of high voltage would have involved danger of fire due to the accumulation of lint and the like at the contacts. Such warpers, however, were of very limited usefulness, since lint, dirt, rust, 80 etc., collecting at the contacts prevented or rendered uncertain the passage of the low-voltage current. I employ a current of sufficiently high voltage to ensure passage of the current between the contacts 36 and 85 37 when the switch is closed, the use of such voltage being rendered safe by reason of the fact that each switch is completely enclosed and thus kept free of lint and dust.

The upper end portions of the conductors 37 of the several tubes 26 comprised in each gate extend up through and are insulated from the cross-bar 18, as shown in Fig. 16, the upper ends of the conductors being secured to a bar 38 mounted on and insulated 90 from the gate. The end of the bar 38 which is adjacent to the pivot pin 19 is connected into an electric circuit by means of a wire 39 (Fig. 17) secured to said bar and coiled around the pivot pin, the coil being insulated from the pivot pin by means of a sleeve 40 of insulating material and being enclosed within a similar sleeve 41. The upper end of the wire 39 is connected to a binding post 42 carried by an insulating 100 block 43 secured to the framework of the creel. The wires 39 of the several bays are electrically connected in any suitable manner into the circuit of an electromagnet 44 (Figs. 22 and 34). When said circuit is 105 grounded through the dropping of any one of the detector arms 27, the electromagnet 44 is energized and thus caused to withdraw a detent which normally holds the 110 brake mechanism inoperative. 115

Referring now to the creel brakes. At any given stop each cheese coasts about the same amount as any of the other cheeses, because the cheeses are all approximately of the same size and because of the character of the braking surfaces. While these surfaces may be of any suitable type, form or arrangement, the present embodiment utilizes the periphery of the cheese as one of the braking surfaces, the other being a polished metal plate. The rubbing of the yarn against the plate in stopping keeps the plate bright so that the surface condition of the plate remains very nearly constant. As 120 stated, the other braking surface is the yarn, 125 130

and as a new surface is constantly being presented to the brake (owing to the unwinding of the yarn) there is no change in the characteristics of this surface due to wear, and other changes due to such causes as temperature and humidity affect all of the cheeses alike.

45 (Figs. 5 and 9) indicates the polished metal plate or arm comprised in each cheese 10 brake. The arm 45 preferably presents a convex surface to the yarn mass and is arranged to bear against the middle of the periphery of the cheese in order that when the arm is pressed against the cheese the latter shall not be tilted or displaced to one side so as to bring its core *b* into contact with an adjacent core. The brake arms 45 are pivotally mounted upon horizontal rock shafts 46 which are supported upon the 20 inner side of the creel frame. Preferably the brake arms 45 extend upwardly from the shafts 46 so that the pressure of the arms against the cheeses shall be in a horizontal or downward direction rather than an upward direction, thus avoiding any lifting of the cheeses with consequent tendency to tilt the latter into contact with adjacent cheeses.

For each brake arm there is a sleeve 47 (Fig. 10) which surrounds and is rigidly 30 secured to the shaft 46 by means of a cotter pin 48. Encircling the middle portion of said sleeve and secured thereto by the pin 48 are two notched flanges 49 and 50. A 35 relatively light torsion spring 51 surrounds the sleeve 47. One end of said spring is hooked to engage the brake arm and the other end is hooked to engage in notches in the flange 49. By shifting the hooked end of the spring from one notch to another, 40 the torsion of the spring may be adjusted to the desired point. The torsion spring 51 normally holds a shoulder 52 (Fig. 11) on the brake arm 45 against a stop shoulder 53 on the flange 49. A stronger torsion 45 spring 54 surrounding the sleeve 47 has one end hooked to engage in notches in the flange 50. The other end of the spring 54 bears against a lug 55 (Fig. 12) on the flange 56 of a collar 57, said collar being 50 rotatably mounted upon the sleeve 47. Normally the torsion spring 54 holds a lug 58 on the flange 56 in contact with a stop lug 59 on the adjacent end of the sleeve 47. 55 When the shaft 46 turns to apply braking pressure to the cheeses, the movement of the stop lug 59 allows the flange 56 also to turn until the surface 60 (Fig. 12) on said flange engages the portion 61 of the brake arm 45 (as in Fig. 13), continuing movement of 60 the shaft 46 causing pressure to be applied to the cheese through the pressure of the surface 60 against the portion 61 of the brake arm.

The normal position of the brake arm 45 65 with relation to the shaft 46 is indicated in

Figs. 11 and 12. When the brake is to be applied, the shaft 46 turns farther than is necessary to place the brake arm against the cheese, as indicated by a comparison of Figs. 12 and 13, the surface 60 being pressed 70 against the portion 61 of the brake arm and the torsion of both springs 51 and 54 being exerted to brake the cheese. The brake-applying movement of the shaft 46 is so rapid that the pressure of both springs is 75 applied practically instantaneously to the cheese. In the return movement of the shaft 46, however, the shaft is first turned far enough to withdraw the surface 60 from the portion 61, but not far enough to place the shoulder 53 against the shoulder 52. In this position of the shaft 46, only the pressure of the spring 51 is being exerted against the cheese through the brake arm 45, this pressure being nearly sufficient to cause 80 slight resistance to rotation of the cheeses. Such resistance is necessary or desirable when the section beam B is being revolved slowly preparatory to shifting to high speed. The drag or yarn-tensioning pressure on the 85 cheeses also is of advantage when the apparatus is at rest, as it prevents the cheeses from revolving too freely when threads are drawn forward in replenishing the creel or piecing up broken threads, or in the event 90 that any of the threads are accidentally disturbed. The drag pressure, however, is necessary only when the cheeses are mounted to revolve very freely, as is the case in the 95 construction herein disclosed. In a creel 100 wherein the cheeses are not mounted to rotate with great freedom, the construction providing the drag pressure may be dispensed with.

The means for turning the shafts 46 comprises two vertical bars 62 (Figs. 6 and 7), one for each of the creel sections 6 and 7, said bars being suitably guided upon the creel sections. Each bar has fixed thereto 105 a rack 63 for each of the shafts 46 of its creel section, except the lowermost shaft. To all of said shafts, except the lowermost shaft, are fixed segments 64 that mesh with the racks 63. On account of limitations of space, the lowermost shaft 46 is not actuated directly from a rack on the bar 62 but is driven from the next higher shaft through sprocket wheels 65 and a sprocket chain 66. To the upper ends of the bars 62 are secured 110 bearings 67 (Fig. 23) to receive the end portions of a horizontal rod 68. Said rod is guided for vertical movement by means of two vertical channel guides 69 (Figs. 3 and 23) secured in the framework 115 of the machine, there being antifriction rollers 70 on the ends of the rod 68. The rod 68 is raised and lowered to actuate the racks by means including rods 71 connected to the rod 68 and pivoted to crank arms 72 (Figs. 120 22 and 23). The crank arms 72 are fixed 125

upon a rock shaft 73. The means for turning the shaft 73 in the direction to apply the brakes comprises an arm 74 fixed upon said shaft, to which arm is anchored one end of a group of tension springs 75. The other end of the group of springs is adjustably connected to a fixed point, as, for example, by means of a bolt 76 extending slidably through an opening 77 in the machine framework, said bolt having a nut 78 (Figs. 3 and 22) thereon. Rigid with the nut 78 is a hand wheel 79 by means of which the tension of the springs 75 may be adjusted. The springs 75 are normally restrained from turning the shaft 73 by means of a dog 80 (Figs. 22 and 24) pivoted at 81 upon an arm 82 fixed on the shaft 73. The dog 80 has a counterweight 83 that normally rests against a stop 84 on the arm 82. 85 is a stop lug on the arm 82 to limit movement of the dog 80 in the opposite direction. The dog 80 normally bears against a flattened surface or shoulder 86 on a pivot 87 rotatably mounted in the machine frame. Rigid with the pivot 87 is an arm 88 (Fig. 22) the end of which underlies a finger 89 (Figs. 22 and 26). The finger 89 is fixed upon a shaft 90 and is normally held in the position shown in Fig. 22 by means of a spring 91 (Fig. 31) connected to an arm 92 which is fixed on the shaft 90, the action of the spring being limited by the engagement of a stop arm 93 on the shaft with a stationary portion 94. Fixed upon the shaft 90 is an arm 95 (Figs. 26 and 29) carrying a lug 96 which is arranged to be engaged by a lug 97 on the hub of an arm 98, said arm being rotatably mounted upon the shaft 90. The arm 98 carries an armature 99 which is arranged to be attracted by the electromagnet 44. 100 is a stop to limit the fall of the armature when the electromagnet is de-energized. It will be seen that when the electromagnet 44 is energized through the fall of any one of the detector arms 27, the armature 99 will be lifted, the projection 97 will strike the projection 96 and cause the shaft 90 to turn against the tension of the spring 91; and the finger 89 will be withdrawn from engagement with the arm 88. The pressure of the dog 80 against the surface 86 will then cause the pivot 87 to turn until the dog 80 is released, whereupon the springs 75, acting through the arm 74, turn the shaft 73 in the direction to apply the brakes to the cheeses. At the end of the brake-applying movement of the shaft 73, the arm 82 is in approximately the position represented in Fig. 27. 101 (Fig. 22) is a buffer against which the arm 88 is thrown under the pressure of the dog 80. As soon as the dog 80 has swung down past the pivot 87, the arm 88 drops back into contact with a stop 102 (Figs. 22 and 26). 65 It will be seen that the pressure for brak-

ing the cheeses is furnished by the springs 75. The torsion springs 51 and 54 constitute yielding means for transmitting such pressure to the cheeses. Being yieldingly connected to the rock shafts 46, the brake arms 45 are enabled to move into contact with all of the cheeses notwithstanding slight differences in the diameter of the cheeses. The springs 75 contract until their force is counterbalanced by the pressure of 75 the torsion springs 51 and 54 against the cheeses.

Since the automatic application of the creel brakes depends upon the energizing of the electromagnet 44, it is desirable that means be provided whereby if the supply of current to the circuit that includes the magnet 44 be cut off, the brakes shall be automatically set. Accordingly there is provided an electromagnet 103 (Figs. 22 and 30), the armature 104 of which is carried by a weighted lever 105 loosely mounted on the shaft 90. On the lever 105 is a lug 106 (Figs. 26 and 30) which is arranged to strike the arm 95 and thus withdraw the finger 89 from the arm 88. The magnet 103 is connected into a normally closed circuit receiving energy from the source that supplies energy to the circuit of the magnet 44. One arrangement of circuits which may be employed is diagrammatically illustrated in Fig. 34. 108 is a switch controlling the supply of electric energy to the circuits of the magnets 44 and 103. Should the supply of current to the conductors 37 fail, as through the opening of the switch 108, the magnet 103 will be deenergized, whereupon the creel brakes will be automatically applied as hereinbefore described.

In order that the flow of current to ground shall be interrupted as soon as the dog 80 has been released, I provide a switch 109 comprising two contacts 110 carried by but insulated from the shaft 73 (Figs. 22 and 34). Each contact 110 is arranged to bridge two contacts 111 included in the circuits containing the conductors 37 and the electromagnet 44. When the shaft 73 turns to apply the creel brakes the contacts 110 are carried out of engagement with the contact fingers 111, thereby interrupting the flow of current to ground through the fallen detector and the magnet 44. As soon as the magnet 44 is thus deenergized the armature 99 drops, allowing the spring 91 (Fig. 22) to place the finger 89 into position above the end of the arm 88.

Simultaneously with the application of the creel brakes, the section beam B is braked. Referring now to Fig. 1: The trunnions of the section beam B are engaged by arms 120 pivoted at 121 to opposite sides of the frame of the warper. The yarn wound around the beam B rests upon a friction driving drum 122. Said drum is fixed upon a shaft 123

which is driven from a shaft 124 by means of a sprocket chain 125 running over sprocket wheels 126 and 127 fixed on the shafts 123 and 124, respectively. The shaft 124 is supported in the rear portion of the warper framework. Said shaft is driven by means of a drive-head fully illustrated and described in my copending application Serial No. 190,502, filed Sept. 10, 1917, said drive-head comprising a pulley or drum 128 mounted upon said shaft midway between the sides of the warper. 129 is a drive-belt extending around the drum 128 for constantly rotating the latter.

15 The beam brake may be of any suitable construction. Herein is shown a brake drum 130 (Figs. 1 and 32) fixed upon the shaft 124 and arranged to be clamped between two brake arms 131. The lower ends of 20 said brake arms are pivotally secured to the framework of the warper at 132 (Fig. 1). Said arms are arranged to be drawn into braking engagement with the drum 130 by tension spring means 133 (Fig. 2^a). Normally the brake arms 131 are held apart and 25 out of engagement with the brake drum by means of a lever 134 and links 135, said links having pin-and-slot connections whereby the lever 134 is permitted to turn after the 30 brake arms 131 have engaged the brake drum. The lever 134 is fixed upon a shaft 136, to which is attached a crank arm 137 (Fig. 1). The crank arm 137 is connected by means of a rod 138 to a crank arm 139 35 which is fixed upon a rock shaft 140. Rigid with the shaft 140 is a crank arm 141 which is connected by means of a rod 142 with a crank arm 143 fixed on the shaft 73. It will be seen that when the shaft 73 is released 40 to the action of the springs 75, the lever 134 will be turned to allow the spring means 133 to draw the brake arms 131 into clamping engagement with the brake drum 130, thereby stopping the rotation of the section beam. By reason of the lost-motion connections between the lever 134 and the links 45 135, the beam-brake pressure is independent of any braking forces being exerted in the creel.

50 The means for turning the shaft 73 to withdraw the brake arms 45 from the cheeses and remove the brake arms 131 from the brake drum 130 comprises a wheel 144 (Figs. 22 and 24) mounted to rotate on an axis 55 parallel with the shaft 73. When the wheel 144 begins to turn, a cam 145 on said wheel engages a roller stud 146 on the arm 82 and lifts said arm. Just before the cam 145 passes out from under the roller stud 146, a cam 147 on the wheel 144 engages a roller 60 148 on the arm 82 and lifts said arm into the position shown in Fig. 24, the roller 148 resting upon a dwell 149. In this position of the arm 82 the rock shafts 46 have 65 been turned far enough to remove the sur-

faces 60 from the portions 61 of the brake arms 45 so that the brake arms are pressed against the cheeses only with the pressure provided by the springs 51. In this position of the parts the brake arms 45 exert 70 only sufficient pressure against the cheeses to prevent too free rotation of the cheeses during the operations incident to the repairing of broken threads and the replenishing of the creel and in preparing to shift 75 to high speed. The arm 82 remains in the position shown in Fig. 24, namely, the drag position, until the operative is ready to set the warper to running at high speed. The wheel 144 is then caused to resume rotation 80 whereupon the cam 150 raises the arm 82 somewhat beyond its normal position, thus carrying the dog 80 past the shoulder 86. As soon as the cam 150 leaves the roller 148, the springs 75 cause the dog 80 to be 85 pressed against the shoulder 86. The arm 82 is thus locked in normal position, the pivot 87 being held against rotation by reason of the engagement of the finger 89 with the arm 88.

The brake-resetting wheel 144 is driven through a train of reduction gears 151 from a drive pulley 152. Alongside the drive pulley 152 is a loose pulley 153. A drive belt 154 (Fig. 1) is arranged to be shifted to and from the pulley 152 by means of a belt shifter comprising a belt-engaging arm 155 and a lever 156, said arm and lever being pivoted on the axis 157 (Fig. 25). Normally the parts 155 and 156 are rigidly 100 connected together by means of a spring plunger 158 carried by the part 155 and engaging a notch 159 in the part 156. A spring 160 acting on the shifter member 156 normally holds the belt on the loose pulley 153. On the rock shaft 73 is fixed a cam 161 (Figs. 23 and 25) which is arranged to operate against a projection 162 on the belt shifter member 156 to swing the belt shifter in the direction to place the drive 110 belt on the tight pulley 152. When the shaft 73 is turned to apply the creel brakes and the beam brake, as hereinbefore described, the cam 161 operates the belt shifter to place the belt on the tight pulley, where- 115 by the wheel 144 is set in motion.

As the wheel 144 raises the arm 82, the cam 161 is withdrawn from the projection 162 on the shifter lever 156. In order to prevent the spring 160 from shifting the belt to the loose pulley until the dwell 149 has reached the roller 148, I provide a lock for the belt shifter, which lock consists of a latch 163 (Figs. 24 and 25) that is pivoted at 164 to the supporting framework, said latch having a shoulder 165 arranged to engage an arm 166 that is rigid with the shifter lever 156. When the shifter lever is moved to place the belt upon the tight pulley, the shoulder 165 on the latch 163 120 125 130

drops behind the arm 166 and thus locks the belt shifter. The means for disengaging the latch 163 from the arm 166 comprises a cam 168 on the wheel 144. When the dwell 149 has reached the roller 148 the cam 168 raises the latch 163 and thus releases the belt shifter to the action of the spring 160, whereupon the belt is shifted to the loose pulley 153. At the same time a brake lug 169 (Fig. 28) which is rigid with the belt shifter arm 155 is pressed against the tight pulley 152 to prevent the wheel 144 from continuing to turn through momentum. When the operative is ready to set the machine in operation under high speed, she manually operates the belt shifter by means hereinafter described to place the belt upon the tight pulley 152, the latch 163 dropping into position to lock the belt shifter as soon as the cam 168 leaves the latch. Immediately after the cam 150 has passed the roller 148, a cam 170 (Fig. 24) on the wheel 144 engages the latch 163 and thus releases the belt shifter to the action of the spring 160 whereupon the belt is shifted to the loose pulley and the brake lug 169 is applied to the tight pulley 152.

Whenever the belt shifter is operated to place the belt on the tight pulley, means is actuated to raise the lever 105 in case said lever has been released by opening of the circuit of the electromagnet 103. This means comprises a link 171 pivoted at one end of the shifter arm 155 and at its other end to one arm of a bell crank 172 pivoted in the machine frame. The other arm of the bell crank is pivoted to a rod 173 guided for substantially vertical movement, the upper end of said rod being bent to underlie the armature 104. Whenever the brakes are applied through an opening of the circuit of the electromagnet 103, the belt 154 is shifted to the tight pulley 152 through the action of the cam 161, and the member 173 is raised to lift the arm 105 into position where the magnet 103 can attract the armature 104 when current is again supplied to said magnet.

After the warper stop motion has stopped the warper, the operative finds the thread-end on the beam and pieces up the thread. To facilitate the finding of the end on the beam, the operative may set the beam in slow rotation by depressing a treadle 174 (Fig. 1) which is pivoted to the warper framework on the axis 175. Rigid with said treadle is an arm 176 which has a pin-and-slot connection with an arm 177 fixed to a shaft 178. Rigid with the shaft 178 is a crank arm 179 (Fig. 33) which is connected by means of the link 180 to one arm of a bell crank 181 which is loosely pivoted upon a shaft 182 carried by the warper framework. The other arm of said bell crank is connected through a link 183 with a frame 184

pivoted to the warper framework at 185. Journaled in the frame 184 is a friction wheel 186 having a beveled or V-shape periphery which is adapted to engage a correspondingly grooved friction wheel 187 (Fig. 32). The latter wheel is rigid with the driving drum 128. Fixed to the friction wheel 186 is a sprocket wheel 188 (Fig. 33) from which power is communicated to a sprocket wheel 189 through a sprocket chain 190. The sprocket wheel 189 is rotatably mounted in the frame 184 and is rigid with a pinion 191 that meshes at all times with a spur gear wheel 192 which is rotatably supported in the warper framework concentrically with the shaft 124. Upon the hub of the gear wheel 192 is formed an annular series of teeth 193 (Fig. 33) which are arranged to engage one of several pawls 194 pivoted to the side of the friction drum 130. A tension spring 195 connected to the frame 184 normally holds the friction wheel 186 out of contact with the friction wheel 187. The action of the spring is limited by contact of the arm 177 (Fig. 1) with a stop portion 196 on the warper framework.

It will be seen that when the operative depresses the treadle 174, the frame 184 will be tilted against the tension of the spring 195 to press the friction wheel 186 against the constantly-rotating friction wheel 187, whereby the pinion 191 will be driven. In the resulting rotation of the spur gear wheel 192, one of the teeth 193 will engage one of the pawls 194 and cause the brake drum 130 and hence the shaft 124 to rotate. The section beam B thereby will be rotated slowly. When the operative has found the thread end she removes her foot from the treadle, whereupon the spring 195 throws out the low-speed mechanism. After having pieced up the thread the operative may again depress the treadle to turn the beam at low speed until the slack in the pieced-up thread has been taken up and all of the threads are running properly. The apparatus is now ready to be operated at high speed. To remove the drag pressure from the cheeses and to connect the high-speed drive to the shaft 124, the operative draws forward a hand lever 197 (Figs. 1 and 2) pivoted in the warper framework. To said lever is pivoted the lower end of a link 198, the upper end of which is connected to one arm of a bell crank 199 (Fig. 20) loosely mounted upon the shaft 140. A rod 200 has a pin-and-slot connection with the other arm of the bell crank 199. Said rod is pivoted to an arm 201 (Figs. 23 and 25) which is rigid with the belt shifter arm 155. Thus it will be seen that when the operative draws the hand lever 197 forward the belt shifter will be actuated to place the belt on the tight pulley 152, whereby the wheel 144 will be set in rotation to swing the arm 82 from the

position shown in Fig. 24 to that shown in Figs. 21 and 22. The drag pressure is thereby removed from the cheeses. At the same time the high-speed driving mechanism is connected to the shaft 124. This is effected by the means to be now described.

The high-speed mechanism (fully described in application Serial No. 190,502) is thrown in by means of a coiled spring 202 (Fig. 32). One end of said spring bears against a collar 203 fixed on the shaft 124, while the other end of the spring bears against a sleeve 204 which is slidably upon the shaft 124. Associated with the sleeve 204 is a roller stud 205 which is engaged by a cam 206 fixed upon the shaft 136. When the shaft 73 is turning into the position shown in Figs. 1 and 21 (wherein the drag pressure is off the cheeses) the train of connections 143, 142, 141, 139, 138, 137 and 136 is actuated to turn the cam 206 into position to allow the spring 202 to connect the high speed mechanism with the shaft 124. The high-speed mechanism then commences to accelerate the section beam.

The detector circuit is closed across the contacts 111 by the switch 109 (Figs. 22 and 34) as the drag pressure is being removed from the cheeses. A short space of time then elapses before the high-speed mechanism begins to accelerate the warp beam. During the interval between the removal of the drag pressure and the starting of the beam, one or more detectors may fall through casual slackening of the corresponding threads. To prevent the brake mechanism from being actuated during this interval and until after the beam has turned so as to take up slackness in any of the threads and thus raise the corresponding detectors, I provide the mechanism shown in Fig. 34. 207 are hooked spring contacts included in the circuit of the detectors. The spring hooks 207 are arranged to engage a contact 208 having the form of a ring. The ring 208 is carried by but insulated from a collar 209 which is slidably mounted upon a spindle 210. A coiled expansion spring 211 bears at one end against a collar 212 on said spindle and at its other end against the collar 209 yieldingly to hold the collar against a shoulder 210^a on the spindle 210. A coiled expansion spring 213 interposed between a stationary part and the collar 212 tends to move the spindle 210 downward to disengage the ring contact 208 from the hook contacts 207. To move the spindle 210 upwardly for the purpose of placing the contact 208 in engagement with the contacts 207, I provide a fly-ball governor comprising bell cranks 214 carried by a ring 215 fixed upon a vertical shaft 216. The bell cranks 214 are arranged to move a spindle 217 which bears against the spindle 210. The shaft 216 is driven from the shaft 124

through spiral gearing 218. As the warp beam is accelerated the governor balls fly outwardly thereby raising the spindle 217 and hence the spindle 210 against the pressure of the spring 213 until the ring contact 208 is engaged by the hook contacts 207. Further upward movement of the spindle 217 is prevented by contact of the bell cranks 214 with their supporting ring 215. When the warper is being stopped the spring 213 expands as fast as the resistance of the governor will permit, but the ring contact 208 is retained by the hook contacts 207 until the downward movement of the spindle 210 has compressed the spring 211 to such a point that it is able to overcome the friction between the ring contact 208 and the hook contacts 207, whereupon the contact 208 springs away from the contacts 207.

When the beam B has been filled, mechanism of any ordinary or preferred construction is automatically actuated to stop the warper by closing the circuit of the electromagnet 44. Such a mechanism is diagrammatically indicated at M in Fig. 34. When the mechanism M operates, the beam brake and the creel brakes are applied as usual, and the resetting mechanism on the creel immediately begins to operate to release the beam brake and substitute the drag pressure for the brake pressure on the cheeses. The beam may then be disconnected from the cheeses by severing the threads in any suitable manner. Preferably the threads are severed by striking them with a rod in the region between the detectors and the cheeses. In thus "whipping out the cheeses" it is desirable, although not essential, that the cheeses be held against rotation. Therefore, means have been provided whereby the creel brakes can be applied without putting the resetting mechanism into operation. It will be remembered that the cam 161 on the shaft 73 (Figs. 22 and 25) actuates the belt-shifter lever 156 whenever the brakes are applied, the normal effect being to shift the belt from the loose pulley 153 to the tight pulley 152, thereby placing the resetting mechanism in operation. To render possible the application of the brakes without placing the resetting mechanism in action, the belt shifter is formed of the two sections 155 and 156 as heretofore described, said sections being normally rigidly connected together by means of the spring plunger 158 (Fig. 25). The plunger 158 may be disengaged from the shifter lever 156 by any suitable means, as, for example, a hand lever 226 (Fig. 1) connected to said plunger by means of a rod or wire 227. 228 (Fig. 3) is a spring anchored at one end to the framework and connected at its other end to a loop 229 (Figs. 23 and 25), said loop being attached to the shifter arm 155. It will be seen that when the plunger 158 is held out

of engagement with the shifter lever 156, the application of the brakes will not result in a shifting of the belt onto the tight pulley.

The means for manually causing an application of the brakes comprises a hand lever 230 (Fig. 2), which hand lever is connected by means of a link 231 (Figs. 2, 3 and 20) to a crank arm 232 loosely mounted on the shaft 140. Rigid with the arm 232 is an arm 233 which is connected through a link 234 to an arm 235 (Figs. 22 and 26). The arm 235 is loosely mounted on the shaft 90 and normally bears against a pin 236 set in the finger 89. It will be seen that when the operator pulls the hand lever 230 forward, the finger 89 will be swung clear of the arm 88, whereupon the springs 75 will cause the brakes to be applied.

When the warper has come to a stop as the result of completion of the yarn mass on the beam B, the operation is as follows: The operative draws forward the hand lever 197, thus causing the resetting mechanism to remove the drag pressure from the cheeses and throw in the high speed drive for the beam. As soon as the threads are under tension, the operative pulls the lever 230 to set the brakes and throw out the drive. As soon as the brakes have been applied, the operative pulls the lever 226, thus disabling the belt shifter and preventing the brakes on both the warper and the creel from being released. Or the operative may grasp the lever 226 first and pull the plunger 158 out, thus disabling the belt shifter, and then while continuing to hold this plunger out she may pull the lever 230 to set the brakes and throw out the drive. The belt shifter having been disabled, the warper brake and the creel brakes stay in the applied position. The threads are then broken by means of a suitable implement, and the beam removed.

When the tridents are being removed from the creel frame, the brake arms 45 swing forward under the pressure of their springs and thus assume a position wherein they interfere with the convenient insertion of tridents into the creel frame. Hence it is desirable to withdraw or completely reset the creel brakes before replacing the used tridents with fresh tridents. But when the type of drive head described in said application Serial No. 190,502 is used, it is desirable that the warper brake remain applied during the creel-replenishing operation. Therefore in order that the resetting mechanism may be placed in action to withdraw the creel brakes without releasing the beam brake or throwing in the high-speed driving mechanism, I provide means for disconnecting the shaft 136 (Fig. 2^a) from the resetting mechanism. This means is shown in Figs. 33 and 35. The arm 137 is loosely pivoted on the shaft 136 and carries a pin 219 that overlies a flange 220 on a crank

arm 221, said crank arm being fixed on the shaft 136. A latch 222 is pivoted at 223 to the crank arm 221 and normally overlies the pin 219, the latch being held in such position by a tension spring 224. When the parts are in the position shown in Figs. 33 and 35, the pin 219 is held between the flanges 220 and the latch 222 so that when the arm 137 is moved the shaft 136 also will be turned. Any suitable means, as, for example, a rod 225 (Fig. 1) may be provided for moving the latch 222 out of engagement with the pin 219. The rod 225 may be released as soon as the pin 219 has passed upwardly beside the latch 222. While holding said latch out, the operative draws forward the hand lever 197, whereby the belt shifter is actuated in the usual manner to shift the belt 154 onto the tight pulley 152. The wheel 144 is thereby set in rotation to move the creel brake shafts from brake position to drag position, whereupon the wheel 144 stops. The operative then again pulls the lever 197, thereby setting the wheel 144 in rotation to remove the drag pressure from the cheeses and place the dog 80 in engagement with the locking shoulder 86, as in Fig. 21. The latch 222 having been held out in the meantime, the upward movement of the arm 137 did not cause the shaft 136 to turn and hence the warper brake was not released and the cam 206 was not actuated to allow the spring 202 to throw in the high-speed driving mechanism. The creel brakes having been thus fully reset, the operative may proceed to replace the tridents one by one with tridents carrying full cheeses.

If desired, the creel may be provided with means for supporting a number of extra cheeses, the yarn from which may be substituted for the yarn from any of the other cheeses. Herein I have shown on each creel frame a stand 237 (Fig. 3), each stand having two spindles 238 which are similar to the spindles of the tridents. Each spindle is arranged to support two cheeses. The stands 237 are omitted in the diagrammatic view, Fig. 2. For each of the extra cheeses there is a brake arm 45, the brakes on each stand being operated from the adjacent shaft 46 through a sprocket chain 239 (Fig. 5) running over sprocket wheels 240 and 241. The sprocket wheel 241 is fixed upon a shaft 242 on which the brake arms are mounted in the manner hereinbefore explained and as illustrated in Fig. 10. Each of the extra cheeses is provided with a detector similar to those previously described, the extra cheese-detectors being connected into the circuit of the electromagnet 44. On the front end of the creel is a horizontal rod 243 (Fig. 3) to support the strands from the extra cheeses above the other threads, in order that such extra strands may run to any space in the comb 244 (Figs. 1 and 2^a) on the warper.

In the rear of the comb 244 is a guide-rod 245 for holding the lower strands out of contact with the back or body of the comb. If desired, a rod 246 may be provided above the rod 245 to keep the topmost strands in the comb. The rod 246 may be raised to give access to the comb when the threads from a new set of cheeses are to be laid in the comb. Forward of the comb is a guide roll 247. The parts 245, 246 and 247 are more fully described in application Serial No. 190,502.

As will be understood from Figs. 2 and 2^b, the cheeses revolve in vertical planes which extend at angles other than right angles to the vertical plane of the comb 244, the detectors serving to guide the threads from the cheeses to the comb.

While any ordinary form of comb may be used on the warper, it is preferable to employ a comb the teeth or spaces of which are so arranged as to indicate the proper locations for the respective threads. In Fig. 1^a is illustrated a comb the spaces of which are divided into sections, there being as many sections as there are columns of cheeses, and each section containing as many spaces as there are cheeses in a column. The sections are differentiated from each other by making the teeth of each section of regularly increasing length, the shortest tooth being at the inner end of the section. As indicated in Fig. 1^a, the space between the two middle sections is made slightly wider than the other spaces, as such middle space receives two threads.

While it will be understood that the operation of replenishing the creel and placing the threads in the warper is susceptible of various modifications, the following is one method that may be pursued. Assuming that the creel frame contains tridents carrying spent cheeses, that the brakes are fully reset or withdrawn, and that there is an empty section beam B in the warper: The gates 12 are opened and the tridents replaced with tridents carrying full cheeses. The operative then pulls the lever 230, thus causing the the creel brakes to be applied and immediately reset to drag position, and the beam brake to be released. The operative then collects the threads of the column of cheeses which is nearest the warper at, say, the right-hand side of the creel, beginning at the top of the column and drawing the thread-ends down to the bottom, the threads twisting together into a bunch. Having thus collected the threads of the four columns of the bay, the operative closes the gate 12, reaches through the gate and picks up the bunches of threads, and draws the bunches of threads over to the warper. As the bunches of threads are drawn to the warper, the plates 34 guide the threads into contact with their respective detector arms,

each of said arms swinging upwardly to permit the threads from higher cheeses to pass up into contact with their proper detectors. Having drawn the bunches of threads to the warper, the operative passes them beneath the guide rod 246, and lays the threads into the spaces in the comb 244, the lowermost thread of the bunch that comes from the column of cheeses nearest the warper being laid in the middle space of the comb, and the remaining threads of said bunch being laid in the comb in regular succession toward the right. The threads of the next column of cheeses are then laid into the next section of the comb, and so on. After all of the threads from the right-hand side of the creel have been deposited in the comb, the threads from the other side of the creel are brought forward and placed in the comb, after which all of the threads are drawn down over the roll 247 into position to be connected to the section beam. As the threads were drawn forward to the warper they rode up the inclined or rounded surfaces of the plates 34, 32 and 31, the direction of pull upon the threads in passing from the cheeses to the warper being such that the threads slid upwardly along said plates, raising the detectors into normal position as shown in full lines in Fig. 14, and sliding down the detectors into running position. As indicated in Fig. 1, the detectors for the different cheeses are located at such heights that the threads shall be able to slide into running position, as just described, the detectors for the lower cheeses being located relatively higher than the detectors for the upper cheeses. It will be seen that the threads are automatically drawn into or associated with their respective detectors in the simple act of drawing the threads forward from the creel to the warper, thereby effecting a great saving in time over warping apparatus wherein the detectors are located on the warper. As is well understood, when the detectors are located on the warper, they are necessarily crowded so closely together that the operative must pay particular attention to the operation of associating successive threads with the proper detectors. Owing to the fact that each thread must be separately associated with its detector, the operative cannot lay the threads into the combs on the old-style warper as rapidly as the same operation can be performed upon the machine herein disclosed. Moreover, in the old-style warper, two combs are required, one at each side of the detectors, and two rolls, whereas in the present machine but one comb and one roll are needed.

The correct placing of the threads in the comb 244 is facilitated by reason of the fact that there is an individual comb section for each bunch of threads, that there

are just enough spaces in each section to accommodate the threads in a bunch, and that the teeth are of graduated length. When laying threads in the comb, the 5 longest tooth of each section serves as a stop in positioning the bunch of threads that belong in the next adjacent section.

The threads of a bunch can be readily laid in their respective spaces in the comb, as the 10 threads "fan out" or diverge from the operative's hand, the bunch of diverging threads being inclined in the same general direction as the upper edge of the comb section. If a thread be missing from a 15 bunch, there will be a vacant space in the comb section, thus immediately bringing the matter to the attention of the operative.

Inasmuch as the thread from the lowest 20 cheese in a column extends through the shallowest space in its section, and so on progressively, a vacant space occurring in the comb upon a stoppage of the warper indicates to the operative the location of the cheese the thread of which is missing, thus 25 expediting the work of piecing-up broken threads.

Since the drive-head is located centrally behind the warper, said head and the drive belt are out of the way of the operative,—a 30 feature of particular value during the replenishing operation and in piecing up threads.

The threads having all been drawn forward and connected to the beam as before 35 described, the operative depresses the treadle 174 to revolve the beam at low speed until it is noted that all of the threads are winding properly. The operative then releases the treadle 174 and pulls forward the starting hand lever 197, thus (through the connections 198, 199 and 200) operating the belt shifter to shift the belt 154 from the loose pulley 153 to the tight pulley 152. The 40 resetting mechanism is thereby placed in operation to remove the drag pressure from the cheeses and throw in the high-speed driving mechanism for the warper. At the end of the resetting operation, the cam 170 (Fig. 24) operates the latch 163 to release 45 the belt shifter to the action of the springs 160 and 228, whereupon the belt is shifted to the loose pulley.

The high-speed driving mechanism accelerates the beam B uniformly and slowly 50 until full winding speed is reached. If during the winding any of the detectors should drop into the dotted-line position shown at *x* in Fig. 14, a circuit will be closed through the electromagnet 44, whereupon 55 the springs 75 apply the creel brakes, the spring means 133 applies the beam brake, and the cam 206 throws out the high-speed driving mechanism. At the same time the belt 154 is shifted to the tight pulley 152 by 60 the cam 161 (Fig. 25) and the resetting

mechanism thus placed in operation to release the beam brake and move the brake shafts 46 from the brake position to the drag position. The beam brake is not released nor the cheeses relieved of the brake pressure until the machine has come to a stop. 70 After correcting the cause of the stoppage, the operative may, by depressing the treadle 174, place the warper in slow operation until she observes that all of the threads are 75 running properly. The drag pressure is then removed and the high-speed driving mechanism thrown in by means of the hand lever 197.

It will be seen that the means for throwing in the high-speed driving mechanism is entirely independent of the means for putting the low-speed driving mechanism in action. In warpers as heretofore constructed the low-speed and high-speed mechanisms have both been controlled by a single treadle partial depression of the treadle throwing in the low speed and complete depression throwing in the high speed. 80 It was thus possible inadvertently to put 85 the machine in high speed when the beam should be rotated slowly.

It will also be apparent that the high-speed-controlling cam 206 is not directly actuated by the operative, but, on the contrary, is actuated by the resetting mechanism and therefore is always operated in a proper and definite manner and in correct sequence with regard to the operation of the 90 creel brakes.

In the event that the operative should pull forward the high-speed starting lever 197 while depressing the treadle 174, the driving mechanism would not be injured, since the pawls 194 (Fig. 33) would simply 95 revolve faster than the teeth 193 and would eventually be withdrawn from the path of said teeth by centrifugal force.

The comb 244 is claimed in my application Serial No. 611,213, filed January 8, 1923. 100

The operative may stop the warper at any desired time by operating the hand lever 230.

As indicated in Figs. 1 and 6, the threads extend directly from the detectors on the creel to the guiding devices on the warper, the detectors thus serving as thread guides, rendering unnecessary the use of any other means on the creel for guiding the running threads. It will be apparent that the devices herein shown for guiding the threads 115 from the cheeses to the beam place a minimum amount of tension on the threads.

As hereinbefore described, each detector consists of a loop providing two points of contact with the thread. Associated with each detector are the two plates 31 and 32. When a thread slackens the detector for that thread swings downwardly, thus causing the thread to be drawn into the form of two 120 loops, as indicated in Fig. 19. By reason of 125

this construction, the detector is adapted to take up some slack before causing stoppage of the apparatus, thereby preventing stoppage from occurring through momentary slackness due, for instance, to some peculiarity in the manner in which the yarn is wound upon the cheese.

If the speed of the beam should decrease by reason of a slowing down or stoppage of the motor or line shaft from which the warper is driven, the breakage of a belt, or from any other cause, the coasting of the cheeses will make the threads slack whereupon the detectors will effect a stoppage of the apparatus before the threads become disarranged.

The beam brake and the creel brakes are so proportioned and adjusted that when the brakes are applied the cheeses and the beam are brought to rest without either severing or seriously slackening the threads.

While I have herein shown a beam warper, the invention in certain of its aspects is not limited to this type of warper.

I claim as my invention:

1. A textile machine having, in combination, means for rotatably supporting the members of a winding couple, a pivoted detector arm located approximately in the plane of rotation of the supply member of the couple and tending to swing in a plane approximately at right angles to the first mentioned plane, a stop to determine the position of the arm under the tension of the thread, and a thread guide having a rounded upper end to direct a thread into contact with the arm, the latter extending above said guide and being located between the guide and the supply member of the couple, said guide extending below the detector arm and there having a guide surface to guide a thread upwardly toward the detector.

2. A textile machine having, in combination, means for rotatably supporting the members of a winding couple, a pivoted detector arm located adjacent to the supply member of the couple, a stop to determine the position of the arm under the tension of the thread, and means to direct a thread into contact with the arm, the latter extending above said directing means and being located between the directing means and the supply member of the couple.

3. A textile machine having, in combination, means for rotatably supporting the members of a winding couple, a detector element located approximately in the plane of rotation of the supply member of the couple, and a guide near the receiving member of the couple, the detector element alone serving to direct the thread to said guide.

4. A warping apparatus having, in combination, a creel, a warper, and a plurality of movable elements each constituting a

combined detector device and thread guide mounted upon the creel so as alone to guide the threads from the creel to the warper, said elements being movable in one direction to effect the detection of an exhausted thread but held under the tension of the thread against movement out of its guiding position.

5. A warping apparatus having, in combination, a creel, a warper, and a plurality of combined detector devices and thread guides mounted on the creel for guiding the threads from the creel to the warper, the threads extending directly from the creel to the warper without intermediate guidance, each such combined device comprising an arm and a stop against which the arm is held by the tension of a thread running in contact therewith, said arm tending to move away from the stop.

6. In a textile apparatus, a pivoted detector arm, a stop against which the arm is held by the tension of a thread running in contact with the arm, said arm tending to move away from the stop, and a guide adjacent to the arm for guiding the thread laterally into contact with the arm in the initial operation of associating the thread with the detector, said guide being normally out of engagement with the thread.

7. A warping apparatus having, in combination, a creel, a warper, a plurality of detectors mounted on the creel, and thread guides mounted on the creel for guiding the threads laterally to the detectors in the initial operation of associating the threads with the detectors, said guides being normally out of engagement with the threads.

8. A warping apparatus having, in combination, a creel, a warper, detector arms pivotally mounted on the creel, a stop against which each arm is held by the tension of a thread running in contact therewith, said arms tending to move away from their stops, and guides on the creel below the respective detector arms for guiding the threads laterally into contact with said arms in the initial operation of associating the threads with the detector arms.

9. A warping apparatus comprising a creel, beam-rotating means, thread-guiding means adjacent to the beam, detectors on the creel, and guides on the creel for directing the threads laterally to the detectors as the threads are initially drawn forward from the creel to the first-mentioned thread-guiding means.

10. A warping apparatus comprising a creel, beam-rotating means, thread-guiding means adjacent to the beam, combined detector devices and thread-guides on the creel for guiding the running threads to the first-mentioned thread-guiding means, and guides on the creel for directing the threads later-

- ally to said combined devices as the threads are initially drawn forward from the creel to the first-mentioned thread guiding means.
11. A warping apparatus having, in combination, a warper, means for supporting a vertical row of yarn masses, a detector arm movably supported near each yarn mass, and guiding means for guiding the threads of the yarn masses laterally into contact with said arms as the threads are drawn in a bunch from the lower portion of the row to the warper, each detector arm being adapted to allow the lateral passage of threads from higher yarn masses into contact with their respective detector arms.
12. A warper creel having, in combination, supports for a plurality of yarn masses to be unwound, a gate arranged to swing into and out of position in front of the yarn masses, and a detector for each yarn mass, said detectors being mounted on the gate.
13. A warper creel having, in combination, supports for a plurality of yarn masses to be unwound, a gate arranged to swing into and out of position in front of the yarn mass, and a detector mounted upon a gate in close proximity to each yarn mass when the gate is in position in front of the yarn masses.
14. A warper creel having, in combination, a plurality of supports for yarn masses to be unwound, a frame movable into and out of position in front of the yarn masses, and detectors for the threads of said yarn masses, said detectors being mounted on said frame.
15. The combination of a support for a yarn mass to be unwound, a detector for the thread of said yarn mass, and a support for said detector movable to carry the detector out of operative position to permit mounting and dismounting of the yarn mass.
16. A warper creel having, in combination, a creel frame, a plurality of creel sections each adapted to support a plurality of yarn masses to be unwound, supports in the creel frame for the creel sections, a gate hinged to the creel frame to swing into and out of place in front of the creel sections, and detectors for the threads of the yarn masses, said detectors being mounted on the creel.
17. A warper creel having, in combination, a creel frame, a plurality of removable creel sections each adapted to support a plurality of yarn masses to be unwound, supports in the creel frame for the creel sections, and a group of detectors for the threads of said yarn masses, said group being movable into and out of operative position in front of the yarn masses.
18. A warper creel having, in combination, supports for a tier of yarn masses to be unwound, a tier of pivoted detector arms for the threads of said yarn masses, each detector arm being located in proximity to its individual yarn mass, and a tier of thread guides, one for each detector arm, each guide extending below its detector arm to guide a thread laterally upward into contact with the detector arm.
19. A warping apparatus having, in combination, a warper, means for supporting a row of yarn masses, a detector arm movably supported near each yarn mass, and guiding means for guiding the threads of the yarn masses laterally into contact with said arms as the threads are drawn in a bunch from one end of the row to the warper, each detector arm being adapted to allow the lateral passage of threads from distant yarn masses in the row into contact with their respective detector arms.
20. A warper creel having, in combination, a plurality of supports for yarn masses to be unwound, a detector supported upon the creel in proximity to each yarn-mass support, and a guide adjacent to each detector for laterally guiding a thread into engagement with the detector.
21. A warper creel having, in combination, supports for a plurality of yarn masses to be unwound, a gate arranged to swing into and out of position in front of the yarn masses, a detector for each yarn mass, said detectors being mounted on the gate, and guides on the gate for guiding threads to the detector.
22. A detector mechanism having, in combination, a pivoted detector arm having two spaced portions across which a thread may run, a stop to determine the position of the arm under the tension of the thread, a thread guide at each side of the detector arm, the upper ends of said guides being rounded to direct a thread into contact with the arm, the latter extending above said guides, and a stationary member between said guides and in a plane passing through the space between the two portions of the arm parallel with the plane of pivotal movement of the arm, said arm tending to move away from said stop to carry a thread into contact with said member and a portion of one of the guides to form loops in the thread.
23. A detector mechanism having, in combination, a pivoted detector arm across which a thread may run, a stop to determine the position of the arm under the tension of the thread, and a thread guide at each side of the detector arm, the upper ends of said guides being rounded to direct a thread into contact with the arm, the latter extending above said guides, said arm tending to move away from said stop to carry a thread into contact with a portion of one of the guides to form a loop in the thread.
24. A detector mechanism having, in combination, a detector arm having a pivot, a contact member mounted upon said pivot and rotatable into an operative and an inoperative position on the pivot, said con-

- tact member being yieldingly held in either of said positions, and a contact member arranged to be engaged by the first mentioned contact member.
- 5 25. A detector mechanism having, in combination, a detector arm having a pivot, a structure within which the pivot is rotatably supported, a contact member upon the pivot within said structure, said contact member being rotatable with reference to the pivot to assume an operative and an inoperative position, the contact member being yieldingly held in either of said positions, and a contact member within said structure arranged to be engaged by the first mentioned contact member, pivotal movement of the first mentioned contact member being limited by the second mentioned contact member and by the enclosing structure.
- 10 26. A detector mechanism having, in combination, a detector arm having a pivot with a non-circular portion, a spring clip embracing said non-circular portion, a contact member at one side of the clip and arranged 15 to be engaged by said clip, and a part at the opposite side of the clip to limit swinging movement of the clip.
- 20 27. A warping apparatus having, in combination, a warper, means for supporting a vertical row of yarn masses, and a detector arm pivotally supported near each yarn mass and tending to swing downwardly, each detector arm being arranged to swing upwardly to allow threads from higher yarn 25 masses to slip laterally past it and move into contact with their respective detector arms as the threads are drawn in a bunch from the lower portion of the row to the warper.
- 30 28. A creel having, in combination, creel brakes, means tending to apply the creel brakes, a detent for said brake-applying means, a normally deenergized electromagnet for withdrawing the detent, detectors arranged to close a circuit through said electromagnet, a member tending to withdraw the detent, and a normally energized electromagnet restraining said member.
- 35 29. A warping apparatus having, in combination, a creel, beam-rotating means, creel braking mechanism, a device controlling the braking mechanism, an electromagnet controlling said device, detectors controlling the electromagnet, and a switch in the circuit of the electromagnet, said switch being controlled by the speed of the beam-rotating means.
- 40 30. A warping apparatus having, in combination, a plurality of supports for yarn masses to be unwound, stopping means, an electromagnet controlling the stopping means, a detector, and a movable support for said detector adapted normally to position it in close proximity to each yarn-mass support, said detectors being arranged to 45 control the circuit of said electromagnet.
- 50 31. A warping apparatus having, in combination, supports for a plurality of yarn masses to be unwound, a gate arranged to swing into and out of position in front of the yarn masses, a detector for each yarn mass, said detectors being mounted on the gate, stopping means, and an electromagnet controlling the stopping means, said detectors controlling the circuit of the electromagnet. 70
- 55 32. A warping apparatus having, in combination, a series of supports for yarn masses to be unwound, a frame movable into and out of position in front of the yarn masses, said frame comprising a tube extending along the series of yarn-mass supports, a series of detectors mounted on said tube, an electric conductor within the tube, said detectors being arranged to establish electrical connection with said conductor, stopping means, an electromagnet controlling the stopping means, and electrical connections between the conductor and the electromagnet. 75
- 60 33. A creel-braking mechanism having, in combination, a brake-controlling arm, thread-controlled means for holding said arm in brake-released position, said arm tending to move into brake-applied position, a cam for moving said arm into brake-released position, said cam having an intermediate dwell portion, a starting and stopping device controlling said cam, means connected to move with the arm for operating the starting and stopping device, means for locking the starting and stopping device in running position, and a device moving with the cam for operating the locking means to unlock the starting and stopping device when the dwell portion is in engagement 80
- 65 34. A warper creel having, in combination, a support for a yarn mass, a brake member to stop the rotation of the yarn mass, means for applying the brake member, two springs of unequal effectiveness for transmitting power from the brake-applying means to the brake member, the less effective spring operating first, means for resetting the brake-applying means, and means for suspending the operation of the resetting means after the pressure of the more effective spring has been withdrawn from the brake member. 85
- 70 35. A warper creel having, in combination, a support for a yarn mass, a brake member to stop the rotation of the yarn mass, means for applying the brake member, and two springs of unequal effectiveness for transmitting power from the brake-applying means to the brake member, the less effective spring operating first. 90
- 75 36. A warping apparatus having, in combination, a beam brake, creel brakes, and mechanism to reset the beam brake and the 95

creel brakes, said resetting mechanism having an idle intermediate thread-tensioning position.

37. A creel-braking mechanism having, in combination, a brake-controlling member, a cam for moving said member into brake-released position, said cam having an intermediate dwell portion, a belt shifter controlling the transmission of power to the cam, said belt shifter tending to move into idle position, a device moving with the brake-controlling member for moving the belt shifter into running position, a latch for locking the belt shifter in running position, a member moving with the cam for disengaging the latch from the belt shifter when the dwell portion is in engagement with the brake-controlling member, means for moving the belt shifter into running position, said latch holding the belt shifter in running position, and a member moving with the cam for disengaging the latch from the belt shifter after the cam has placed the brake-controlling member in brake-released position.

38. A creel-braking mechanism having, in combination, a brake-controlling arm, thread-controlled means for holding said arm in brake-released position, said arm tending to move into brake-applied position, a cam for moving said arm into brake-released position, said cam having an intermediate dwell portion, a belt shifter controlling the transmission of power to the cam, said belt shifter tending to move into idle position, a device moving with the arm for moving the belt shifter into running position, a latch for locking the belt shifter in running position, a member moving with the cam for disengaging the latch from the belt shifter when the dwell portion is in engagement with the arm, manual means for moving the belt shifter into running position, said latch holding the belt shifter in running position, and a member moving with the cam for disengaging the latch from the belt shifter after the cam has placed the arm in brake-released position.

39. A creel-braking mechanism having, in combination, a brake-controlling member, means to reset said member, mechanism to actuate the resetting means, means to cause stoppage of the resetting means in intermediate position, and manual means for operating the mechanism that actuates the resetting means.

40. A creel-breaking mechanism having, in combination, a brake-controlling member, means to reset said member, mechanism to cause actuation of the resetting means, the brake-controlling member being arranged to operate said mechanism, means to cause stoppage of the resetting means in intermediate position, and manual means for operating

the mechanism that causes actuation of the 65 resetting means.

41. A warper creel having, in combination, a support for a yarn mass, a brake member to stop the rotation of the yarn mass, means for applying the brake member into and out of braking position, two springs of unequal strength for transmitting power from the brake-applying means to the brake member, the weaker spring operating first, and means for resetting the brake-applying means step by step.

42. A warping apparatus having, in combination, a creel, beam-rotating means, a beam brake, means to apply a yarn-tensioning pressure to the yarn masses in the creel, 80 means to apply the beam brake, means to apply the tensioning means, means automatically to release the beam brake, and manually-operable means for subsequently releasing the tensioning means.

43. A creel having, in combination, a brake member having a yarn-mass-stopping position and a yarn-tensioning position, means to reset the brake member, said means having a dwell position corresponding to the 90 yarn-tensioning position of the brake member, and manually-operable means for restarting the resetting means from said dwell position.

44. A warping apparatus having, in combination, a creel, beam-rotating means, a beam brake, means to apply a yarn-tensioning pressure to the yarn masses in the creel, means to apply the beam brake, means to apply the tensioning means, means automatically to release the beam brake, and independent means to release the tensioning means.

45. A warping apparatus having, in combination, a creel, beam-rotating means, a beam brake, means to apply a yarn-tensioning pressure to the yarn masses in the creel, means for applying the beam brake, means to apply the tensioning means, a cam for releasing the beam brake, and a cam for releasing the tensioning means, said cams operating successively.

46. A warping apparatus having, in combination, a creel, beam-rotating means, a beam brake, means to apply a yarn-tensioning pressure to the yarn masses in the creel, means to apply the beam brake, means to apply the tensioning means, means to release the beam brake, and means for subsequently releasing the tensioning means.

47. A warping apparatus having, in combination, beam-rotating means, a device to place the beam-rotating means in operation, a creel, creel brakes, mechanism to reset the creel brakes and actuate said device, said resetting mechanism having an idle intermediate thread-tensioning position, starting means actuated when the creel brakes

are applied for placing the resetting mechanism in operation, manual means to disable said device, manual means to place the resetting mechanism in operation from said 5 idle position, manual means to disable the starting means, and means for causing application of the creel brakes.

48. A warping apparatus having, in combination, beam-rotating means, a device to 10 place the beam-rotating means in operation, a beam brake, a creel, creel brakes, mechanism to reset the beam brake and the creel brakes and actuate said device, said resetting mechanism having an idle intermediate 15 thread-tensioning position, starting means actuated when the creel brakes are applied for placing the resetting mechanism in operation, manual means to disable said device, manual means to place the resetting 20 mechanism in operation from said idle position, manual means to disable the starting means, and manual means for causing application of the creel brakes.

49. A warping apparatus having, in combination, beam supporting means, a high speed drive for the beam, a device to throw in the drive, a creel, creel brakes, mechanism to reset the creel brakes and actuate the throwing-in device, a belt shifter actuated when the creel brakes are applied for causing operation of the resetting mechanism, manual means to disable the throwing-in device, manual means to actuate the belt shifter to place the resetting mechanism 30 in operation, manual means to disable the belt shifter, and manual means for causing application of the creel brakes.

50. A warping apparatus having, in combination, beam supporting means, a high speed drive for the beam, a device to throw in the drive, a creel, creel brakes, mechanism to reset the creel brakes and actuate the throwing-in device, said resetting mechanism having an idle intermediate thread-tensioning position, a belt shifter actuated when the creel brakes are applied for causing operation of the resetting mechanism into said idle position, manual means to disable the throwing-in device, manual means 45 to actuate the belt shifter to place the resetting mechanism in operation from said idle position, manual means to disable the belt shifter, and manual means for causing application of the creel brakes.

51. A warping apparatus having, in combination, beam supporting means, a high speed drive for the beam, a device to throw in the drive, a beam brake, a creel, creel brakes, mechanism to reset the beam brake and the creel brakes and actuate the throwing-in device, said resetting mechanism having an idle intermediate thread-tensioning position, a belt shifter actuated when the creel brakes are applied for causing opera-

tion of the resetting mechanism into said 65 idle position, manual means to disable the throwing-in device, manual means to actuate the belt shifter to place the resetting mechanism in operation from said idle position, manual means to disable the belt shifter, 70 and manual means for causing application of the creel brakes.

52. A warping apparatus having, in combination, beam rotating means, a drive for 75 the beam rotating means, a cam controlling said drive, a creel, yarn-tensioning means in the creel, mechanism for resetting the yarn-tensioning means, said mechanism being arranged to operate the cam, and means for disconnecting the cam from said 80 mechanism.

53. A creel braking mechanism having, in combination, a brake-controlling arm, a member for holding said arm in brake-released position, said arm tending to move 85 into brake-applied position, a cam for moving said arm into brake-released position, said cam having an intermediate dwell portion, a starting and stopping device controlling said cam, means connected to move 90 with the arm for operating the starting and stopping device, a latch for locking the starting and stopping device in running position, a device moving with the cam for disengaging the latch from the starting and 95 stopping device when the dwell portion is in engagement with the arm, manual means for operating the starting and stopping device, and manual means for disengaging the holding member from the arm.

54. A creel having, in combination, braking mechanism, a cam for resetting the braking mechanism, a belt shifter controlling the transmission of power to the cam, said belt shifter comprising a belt-engaging section 105 and an arm, a locking device for connecting said section and arm together, springs connected to said section and arm for moving said section into idle position, a member moving with the brake mechanism for operating on said arm to place the belt shifter in running position, and means for operating said locking device to disconnect the belt-engaging section from said arm.

55. A warping apparatus having, in combination, a creel, creel brakes, mechanism to reset the creel brakes, a belt shifter actuated when the creel brakes are applied for causing operation of the resetting mechanism, manual means to actuate the belt shifter 115 to place the resetting mechanism in operation, manual means to disable the belt shifter, and manual means for causing application of the creel brakes.

56. A warping apparatus having, in combination, a creel, creel brakes, mechanism to reset the creel brakes, a belt shifter for causing operation of the resetting mechanism,

- devices to actuate the belt shifter, manual means to disable the belt shifter, and manual means for causing application of the creel brakes.
57. A warping apparatus having, in combination, a creel, creel brakes, mechanism to reset the creel brakes, a belt shifter actuated when the creel brakes are applied for causing operation of the resetting mechanism, means to actuate the belt shifter to place the resetting mechanism in operation, means to disable the belt shifter, and means for causing application of the creel brakes.
58. A warping apparatus having, in combination, a creel, creel brakes, mechanism to reset the creel brakes, a belt shifter for causing operation of the resetting mechanism, devices to actuate the belt shifter, means to disable the belt shifter, and means for causing application of the creel brakes while the belt-shifter is disabled.
59. A creel-braking mechanism having, in combination, a brake-controlling arm, thread-controlled means for holding said arm in brake-released position, said arm tending to move into brake-applied position, a cam for moving said arm into brake-released position, said cam having an intermediate dwell portion, a starting and stopping device controlling said cam, means for automatically operating the starting and stopping device, manual means for operating the starting and stopping device, and manual means for releasing said arm to movement.
60. A creel having, in combination, creel brakes, means for automatically causing application of the creel brakes, means to reset the creel brakes, means to disable the resetting means, and manual means to cause application of the creel brakes.
61. A warper creel having, in combination, a creel frame, a plurality of creel sections each adapted to support a plurality of yarn masses to be unwound, supports in the creel frame for the creel sections, a gate hinged to the creel frame to swing into and out of place in front of the creel sections, and slack-take-ups for the threads of the yarn masses, said slack-take-ups being mounted on the creel.
62. A warping apparatus having, in combination, a creel, pivoted detectors on the creel having notches through which the threads may run, beam-rotating means, thread-guiding means adjacent to the beam-rotating means, and a guide plate adjacent to each detector, the threads riding up said plates as the threads are drawn forward to the thread-guiding means, the direction of pull on the threads in passing from the yarn masses in the creel to said thread-guiding means being such that the threads slide upwardly along said plates, raising the detectors into normal position and sliding down the detectors into running position.
63. A warping apparatus having, in combination, a creel, pivoted detectors on the creel having notches through which the threads may run, beam-rotating means, thread-guiding means adjacent to the beam-rotating means, and a guide plate adjacent to each detector, the threads riding up said plates as the threads are drawn forward to the thread-guiding means, the direction of pull on the threads in passing from the yarn masses in the creel to said thread-guiding means being such that the threads slide upwardly along said plates, raising the detectors into normal position and sliding down the detectors into running position.
64. A warping apparatus having, in combination, a creel, pivoted detectors on the creel having notches through which the threads may run, beam-rotating means, thread-guiding means adjacent to the beam-rotating means, and guide means adjacent to each detector, the direction of pull on the threads in passing from the yarn masses in the creel to said thread-guiding means being such that the threads slide upwardly along said guide means, raising the detectors into normal position and sliding down the detectors into running position.
65. A warping apparatus comprising a creel, beam-rotating means, thread-guiding means adjacent to the beam, detectors on the creel, and means for directing the threads laterally to the detectors as the threads are initially drawn forward from the creel to the first-mentioned thread-guiding means.
66. A warping apparatus comprising a creel, beam-rotating means, thread-guiding means adjacent to the beam, combined detector devices and thread-guides on the creel for guiding the running threads to the first-mentioned thread-guiding means, and means for directing the threads laterally to said combined devices as the threads are initially drawn forward from the creel to the first-mentioned thread-guiding means.
67. A warping apparatus having, in combination, beam-rotating means, a device to place the beam-rotating means in operation, a beam brake, mechanism to reset the beam brake and actuate said device, and starting means actuated when the beam brake is applied for placing the resetting mechanism in operation.
68. A warping apparatus having, in combination, creel brakes, and mechanism to slide upwardly along said plates, raising the detectors into normal position and sliding down the detectors into running position, the detectors for the different yarn masses being located at such heights that the threads shall be able to slide into running position, the detectors for the lower yarn masses being located relatively higher than the detectors for the upper yarn masses.

reset the creel brakes, said resetting mechanism having an idle intermediate thread-tensioning position.

69. A warping apparatus having, in combination, a creel, a warper, beam-rotating means, means for driving the beam-rotating means at high speed, a high-speed-controlling member, creel brakes, and creel-brake-resetting mechanism arranged to actuate 10 said member.

70. A warping apparatus having, in combination, beam-rotating means, a beam brake, creel brakes, and means to reset the beam brake and the creel brakes, said resetting means being arranged to restart the beam-rotating means.

71. A warping apparatus having, in combination, creel brakes, beam-rotating means, and creel-brake controlling means arranged 20 to restart the beam-rotating means.

72. A warping apparatus having, in combination, beam-rotating means, power means to place the beam-rotating means in operation, and manual means to disable the 25 second-mentioned means.

73. A warping apparatus having, in combination, beam-rotating means, power means to place the beam-rotating means in operation, and manual means to control the section 30 and-mentioned means.

74. A warping apparatus having, in combination, a creel, a warper, creel-braking mechanism, a device controlling the braking mechanism, an electromagnet controlling 35 said device, detectors controlling the electromagnet, and a switch in the circuit of the electromagnet, said switch being operated by the warper.

75. A creel having, in combination, creel 40 brakes, means tending to apply the creel brakes, a detent for said brake-applying means, a normally deenergized electromagnet for withdrawing the detent, and detectors arranged to close a circuit through 45 said electromagnet.

76. The combination of a yarn-mass support, a member supported in position to bear upon the yarn surface of the yarn-mass, and means to press said member 50 against the yarn-mass with a relatively light pressure to tension the yarn and a relatively heavy pressure to stop the yarn-mass.

77. The combination of means to support 55 a cheese for rapid rotation on a horizontal axis, a member mounted on a horizontal axis in position to bear upon the periphery of the cheese, and means to press said member against the cheese with a relatively light pressure to tension the yarn and a relatively 60 heavy pressure to stop the cheese.

78. A warping apparatus comprising 65 means to support and rotate a beam, a roll above the beam to guide the threads to the beam, a comb behind the roll to guide the threads to the roll, a creel adapted to sup-

port cheeses for rotation in vertical planes which extend at angles other than right angles to the plane of the comb, and detectors on the creel which alone serve to guide the threads from the cheeses to said comb. 70

79. A high-speed creel having supports for a vertical row of cheeses to be unwound, a vertical tube extending along the row of cheeses, an electric conductor extending longitudinally of and within the tube, a series 75 of detector arms pivoted on the tube, there being one detector for each cheese, and a contact within the tube and connected to each detector arm and arranged to engage said conductor.

80. A creel having supports for a row of yarn masses to be unwound, a tube extending parallel with the row of yarn masses, an electric conductor extending longitudinally of and within the tube, a series of detector 85 arms pivoted on the tube, there being one detector for each yarn mass, and a contact within the tube and connected to each detector arm and arranged to engage said conductor. 90

81. The method of replenishing a warper creel having detectors mounted thereon, and connecting the threads of the new yarn masses with the warp beam which includes the steps of first filling the creel with yarn 95 masses and subsequently drawing the threads of the yarn masses forward to the warper whereby the detectors are automatically threaded.

82. The method of replenishing a warper 10 creel having detectors mounted thereon, and connecting the threads of the new yarn masses with the warp beam which includes the steps of filling the creel with vertical rows of yarn masses, collecting the threads 10: of one or more rows into bunches, the threads of each row forming a separate bunch, and drawing the bunches forward to the warper one after another, beginning with the bunch nearest the warper whereby 11 the detectors are automatically threaded.

83. The method of associating the threads of a series of yarn masses with their respective detectors which consists in collecting 11: said threads into a bunch and drawing the bunch of threads past the detectors and away from the yarn masses.

84. The method of associating the threads of a vertical row of yarn masses with detectors located approximately opposite the respective yarn masses which consists in collecting the threads of the yarn masses, beginning at the top of the row and drawing the thread ends down to the bottom, and drawing the bunch of threads past the detectors and away from the yarn masses. 120

85. The method of controlling a warping apparatus which consists in simultaneously braking the beam and the supply yarn masses so as to stop their rotation, subse- 130

quently relieving the beam of braking force and reducing the braking force on the supply yarn masses to a drag pressure, and finally withdrawing the drag pressure.

5 86. The method of controlling the rotation of a freely revoluble yarn mass in a creel which consists of applying sufficient braking pressure to the yarn mass to stop its rotation and then reducing the braking pressure to a point where the yarn mass is held against casual rotation but may be rotated by tension on the yarn.

In testimony whereof, I have hereunto set my hand.

HOWARD D. COLMAN.
